UNITED STATES PATENT OFFICE.

RAYMOND G. MOORE, OF BRIDGEPORT, CONNECTICUT, ASSIGNOR TO THE BASSICK COMPANY, OF BRIDGEPORT, CONNECTICUT.

LATCH.

Application filed May 8, 1926. Serial No. 107,541.

The present invention relates to an improved automobile door latch, and has for an object to provide a latch of this character, having both an inside and an outside 5 operating handle, and in which the outside handle may be rendered ineffective in its operation by means controlled from the inside. The latch is especially adapted for use upon doors of closed cars, being applied 10 to all but one of the doors, and which latter is adapted to be locked from the outside.

Heretofore it has been the practice to lock the outside handle, or the latch bolt, against movement, either through manipulation of 15 the inside handle, or through separate inside locking means, so that by exerting a sufficient force upon the locked outside handle the locking means could be forced or broken, and the latch bolt retracted to open 20 the door. It is proposed, in the present embodiment of the invention, to render operation of the outside handle ineffective to operate the bolt, without locking it against turning, however, and which cannot 25 be forced to effect retraction of the bolt.

A further object is to provide a latch in which the outside handle is rendered ineffective through a movement of the inside handle in reverse direction to the normal 30 retracting movement, so that in order to restore the operative relation of the outside handle, it is only necessary to move the inside handle in its normal retracting direction.

35 Another object is to provide a latch construction in which the inside handle mechanism is adapted to operate directly with the bolt independently of the outside retracting means, while the outside handle mechanism 40 operates upon the bolt through an intermediate member.

With the above and other objects in view, embodiments of the invention are shown in the accompanying drawings, and these 45 embodiments will be hereinafter more fully described with reference thereto, and the invention will be finally pointed out in the claims.

In the drawings:

50 Fig. 1 is a plan elevation of an automobile door latch, according to the present embodiment of the invention, and showing the same in its normal operative relation;

55 Fig. 2 is a plan elevation, with the cover plate removed, and showing the parts in

the relation in which operation of the outside handle is rendered ineffective;

Fig. 3 is a plan elevation of a slightly modified form of construction, and showing the same in its normal operative relation; 60

Fig. 4 is a longitudinal sectional view, taken along the line 4-4 of Fig. 3; and

Fig. 5 is a plan elevation, with the cover plate removed, and showing the parts in the relation in which operation of the outside 65 handle is rendered ineffective.

Similar reference characters indicate corresponding parts throughout the several figures of the drawings.

Referring to the drawings, and more particularly to Figs. 1 and 2 thereof, the embodiment of the invention shown therein comprises a sheet metal frame or base plate 10, having a face flange 11 bent therefrom at one end, within which a rectangular opening 12 is provided, a lip flange portion 13 of the metal cut from said opening being bent inwardly in parallel spaced relation to the plate 10 to form a bearing for the latch bolt. 70

The latch bolt 14 is slidably engaged at its relatively thick nose portion 15 in the opening 12, and near its inner end is provided with a slot 16 engaged with a fixed guide roller 17 secured to the plate 10, a coil spring 18 engaged with the inner end of said bolt normally pressing it to its projected position. The bolt is retained against displacement by means of a flat cover plate 19, flanged at its upper and lower edges, as 75 at 20, and secured to the plate 10 by lugs 21 inserted through slots 22 in said plate and bent over upon the outer surface thereof. 80

The main part of the bolt within the casting may preferably be formed of flat sheet 85 metal, while the nose portion may be a forging riveted thereto.

At the rearward end of the bolt there is provided an upwardly projecting vertical extension 23 having a longitudinal slot 24 extending rearwardly from the forward vertical edge thereof, and in upwardly spaced relation to the upper edge of the bolt. The vertical edge portion of the extension 23 above the slot 24 is engaged by the inner handle roll-back 25, the hub 26 of which has bearing in apertures formed in the base and cover plates 10 and 19. 100

The inner handle roll-back is adapted through rotation in one direction (counter- 110

clockwise) to retract the latch bolt in the usual manner, and by partial rotation in opposed direction, and as will presently more fully appear, to render operation of the outside handle mechanism ineffectual.

The outside handle roll-back 27 has its hub 28 rotatably engaged in apertures in the plates 10 and 19 adjacent the face flange 11, and is adapted to actuate the bolt through an intermediate slide and rocking 10 retracting member 29, including a forwardly projecting portion 30 engaged with the roll-back, an upper arm portion 31 extending above the inside handle roll-back, and a lower arm portion 32 normally engaging the upper surface of the bolt adjacent the extension 23. The member 29 is provided with a longitudinal slot 33, substantially parallel with the bolt in the normal operative position of said member, and in which is engaged a fixed guide stud 34 secured to the casing. The member 29 is connected to the roll-back 27 by means of a link 35 having relatively loose connection 20 at one end; and a spring 36 coiled about the stud 34, having one end engaged by a lug 37 struck up from the casing and its other end engaged with a stud 38 provided at the lower forward portion of said member, yieldingly presses the member and the outside handle roll-back into their normal positions and tends to rotate said member in clockwise direction about the stud 34.

The inside handle roll-back is provided 35 with a camming portion 39, normally out of contact with the upper arm 31 of the retracting member 29, and adapted upon partial rotation of the roll-back in reverse or clockwise direction to rock the member 29 upwardly, bringing the arm 32 into line with the slot 24 of the bolt extension 23. A V-portion 40 of the roll-back engaged by a spring 41, secured about studs 42 and 43 and provided at its end with an angular 45 portion 44, is adapted through engagement above and below said portion 44 to limit and retain the normal and reversely moved positions respectively of the roll-back.

The operation is as follows:

50 As shown in Fig. 1, in which the parts are in their normal operative relation, the latch bolt is retracted from the inside by the inside handle, the roll-back 25 being rotated in counter-clockwise direction and bearing directly upon the extension 23 of the bolt. It is retracted from the outside by the outside handle, the roll-back 27 being rotated in clockwise direction, and, through movement of the intermediate member 29, as shown in dotted lines in Fig. 1, retracting the bolt.

In order to render operation of the outside handle ineffective to retract the bolt, the inside handle is moved through a partial 65 rotation, in opposed direction to its

normal retracting movement (Fig. 2) bringing the cam portion 39 into engagement with the upper arm 31 of the member 29, rocking the latter about the stud 34 to a point where the lower arm 32 is in line 70 with the slot 24 of the latch extension 23. Upon actuation of the outside handle in this relation, the member 29 is shifted inwardly, as shown in dotted lines, but is ineffectual to retract the latch bolt, the arm 75 32 moving freely within the slot 24.

The normal operative relation of the outside handle is restored upon moving the inside handle in retracting direction, the initial movement disengaging the cam portion 80 39 from the arm 31 and causing the arm 32 to reengage the bolt below the slot 24, and the continued movement causing retraction of the bolt.

Under all conditions the latch bolt is free 85 to be retracted independently of the handles, that is, by pressure directly applied at its nose end, as in slamming the door closed.

In Figs. 3 to 5 I have illustrated a modified form of the invention, in which the member 29 is provided with a pivot stud 50 projecting at each side, and which slidably and pivotally engages horizontal slots 51 and 52 provided in the plates 10 and 19, a helical spring 53 being tied between the lower forward corner of said member 29 and a lug 54 struck up from the casing, the action of this spring being substantially the same as the spring 36 of the first form to yieldingly move the member 29 and the outside roll back into their normal positions and to rotate said member 29 in clockwise direction. In this embodiment the sliding movement of the member 29, in both the operative relation 100 as shown in Fig. 3 and in the inoperative relation as shown in Fig. 5, is in a direction parallel to the direction of movement of the bolt.

I have illustrated and described preferred 110 and satisfactory embodiments of the invention, but it will be obvious that changes may be made therein, within the spirit and scope thereof, as defined in the appended claims.

Having thus described my invention, what I claim and desire to secure by Letters Patent is:

1. In a latch, a latch bolt, retracting means for said bolt including inside and outside manually operable means, a retracting member interposed between said outside retracting means and said bolt, said inside retracting means adapted to retract said bolt independently of said member and means associated with said inside retracting means adapted upon manipulation of the latter in a non-bolt-retracting direction to remove said retracting member from operative relation with the bolt.

2. In a latch, a latch bolt, retracting

means for said bolt including inside and outside manually operable means, a retracting member interposed between said outside retracting means and said bolt, said inside means engaging directly with the bolt and adapted to retract the same independently of said member, and means associated with said inside retracting means adapted upon manipulation of the latter in a non-bolt-retracting direction to remove said retracting member from operative relation with the bolt.

3. In a latch, a latch bolt, retracting means for said bolt including inside and outside manually operable means, a retracting member interposed between said outside retracting means and said bolt, said inside retracting means adapted to retract said bolt independently of said member, and means carried by said inside retracting means engaging directly with said retracting member and adapted upon manipulation of said inside retracting means in a non-bolt-retracting direction to remove said retracting member from operative relation with the bolt.

4. In a latch, a latch bolt, retracting means for said bolt including inside and outside manually operable means, a retracting member interposed between said outside retracting means and said bolt, said inside retracting means engaging directly with the bolt and adapted to retract the same independently of said member and including a portion adapted to engage directly with said retracting member, whereby movement of said inside retracting means in one direction is adapted to retract the bolt and in the other direction is adapted to remove said retracting member from operative relation with said bolt.

5. In a latch, a latch bolt, retracting means for said bolt including inside and outside manually operable means, a retracting member interposed between said outside retracting means and said bolt, said inside retracting means adapted to retract said bolt independently of said member, said inside retracting means including means operatively related to said retracting member, whereby movement of said inside retracting means in one direction is adapted to retract the bolt and in the other direction is adapted to remove said retracting member from operative relation with the bolt.

55 6. In a latch, a latch bolt, retracting means for said bolt including inside and outside manually operable means, a retracting member interposed between said outside retracting means and said bolt and including portions adapted to respectively engage said bolt and said inside retracting means, said inside retracting means adapted upon manipulation in a non-bolt-retracting direction to remove said retracting member from operative relation with the bolt and

upon manipulation in the other direction to retract said bolt independently of said member.

7. In a latch, a latch bolt, retracting means for said bolt including inside and outside manually operable means, a retracting member interposed between said outside retracting means and said bolt and including spaced arms adapted to respectively engage said bolt and said inside retracting means, said inside retracting means adapted upon manipulation in a non-bolt-retracting direction to move said retracting member whereby said bolt engaging arm is removed from operative relation with the bolt.

8. In a latch, a latch bolt, retracting means for said bolt including inside and outside manually operable means, a slidably and pivotally mounted retracting member interposed between said outside retracting means and said bolt, said member adapted to have sliding movement imparted thereto by said outside retracting means to retract the bolt, and means associated with said inside retracting means adapted upon manipulation of the latter in a non-bolt-retracting direction to pivotally move said retracting member out of operative relation with said bolt, whereby sliding movement thereof is ineffective to retract the bolt.

9. In a latch, a latch bolt having a transverse extension, retracting means for said bolt including inside and outside manually operable means, said inside retracting means engaging directly with said transverse extension, a retracting member interposed between said outside retracting means and said bolt, and engaging said transverse extension thereof, and means associated with said inside retracting means adapted upon manipulation of the latter in a non-bolt-retracting direction to remove said retracting member from operative relation with the bolt and upon manipulation in the other direction to retract said bolt independently of said member.

10. In a latch, a latch bolt having a transverse extension provided with a longitudinal slot, retracting means for said bolt including inside and outside manually operable means, a retracting member interposed between said outside retracting means and said bolt and including a portion engaged with said transverse extension, and means associated with said inside retracting means adapted upon manipulation of the latter in a non-bolt-retracting direction to move said bolt engaging portion of the retracting member into line with said slot, whereby movement of said retracting member is ineffective to retract the bolt.

11. A latch comprising a casing, a spring controlled latch bolt slidably mounted therein, an outer handle roll-back, a member pivotally connected therewith, an inner

handle roll-back coacting with said latch mechanism, a second spring coacting therewith, bolt, and a spring coacting with the inner handle roll-back, said inner handle roll-back mechanism and controlled by the inner handle mechanism and adapted to be moved into a position to prevent operation of the latch bolt by the outer handle roll-back.

12. A latch comprising a slidable latch bolt, a spring coacting therewith, an outer handle mechanism, an inner handle mecha-

Signed at Bridgeport, in the county of Fairfield, and State of Connecticut, this 4th day of May, 1926.

RAYMOND G. MOORE.
